US00D666056S

(12) **United States Design Patent**
Boozer et al.

(10) **Patent No.:** **US D666,056 S**
(45) **Date of Patent:** **** Aug. 28, 2012**

(54) **BLENDER TAMPER**

(75) Inventors: **Richard D. Boozer**, Wakeman, OH (US); **Robert M. Ulanski**, Broadview Hts., OH (US)

(73) Assignee: **Vita-Mix Corporation**, Olmsted Falls, OH (US)

(**) Term: **14 Years**

(21) Appl. No.: **29/417,744**

(22) Filed: **Apr. 9, 2012**

(51) **LOC (9) Cl.** **07-02**

(52) **U.S. Cl.** **D7/412; D7/376; D7/378; D7/384**

(58) **Field of Classification Search** ..... **D7/300.2, D7/301–313, 316–319, 356–357, 368, 372–386, D7/391–398, 412–415, 515, 605, 665, 679, D7/691; D13/133, 154; 99/348, 467, 492, 99/508–513; 222/215; 241/30–37.5, 101.01–101.2, 241/166–169.2, 172, 199.12, 282.1–282.2, 241/285.1–285.3, 291, 292.1; 366/64–67, 366/98, 129, 142–147, 191–211, 241–254, 366/262, 279–292, 325.8, 325.92, 341–347; 416/75–77, 70 R, 163**
